UNITED STATES PATENT OFFICE

EUGENE F. MARTINET, OF CLEVELAND, OHIO, ASSIGNOR TO THE DUAL SPEEDOMETER COMPANY, OF CLEVELAND, OHIO, A CORPORATION OF OHIO

SPEED-INDICATING MECHANISM

Application filed January 14, 1929. Serial No. 332,256.

Speed indicating devices have already been proposed in which there is a running index capable of being stopped at will to retain an indication of the running speed at any desired moment. This is of considerable advantage to traffic officers and to users generally where accuracy is wanted. In the present invention however, I have now made available not only all the utilities of a stop-indication of any desired speed, but in addition the running speed indication is continually available without interference or interruption by the retained indication.

To the accomplishment of the foregoing and related ends, the invention, then, consists of the features hereinafter fully described, and particularly pointed out in the claims, the following description and the annexed drawing setting forth in detail certain structure embodying the invention, such being illustrative however of but one of the various ways in which the principle of the invention may be employed.

In said annexed drawing:—

Fig. 1 is a plan view showing an embodiment of the invention; Fig. 2 is a similar view with the cover assembly removed; Fig. 3 is a fragmentary axial section; Fig. 4 is a fragmentary side elevation; Fig. 5 is an inside view of the cover plate assembly; Fig. 6 is a sectional detail taken on a plane indicated by the line VI—VI, Fig. 5; and Fig. 7 is an enlarged sectional detail.

In its general aspects, the invention contemplates a running index for showing the speed variations at all times and an index optionally controllable to retain an indication of the running speed at any desired instant. Preferably a maximum indicating index is also associated with the running index.

The particular mechanism by which the speed is translated to the running index is immaterial to the present invention and will be understood to be of any convenient character, whether centrifugal, magnetic, etc., and in the form of the invention illustrated is housed in a casing 1, a part only of which is shown, and the shaft directly actuating the indexing member, here an index hand 2, projects at 3 through a dial plate 4. A maxi-

mum indicating hand 5 where desired may be mounted so as to be propelled forward by the running hand and by suitable mechanism, the detail of which is immaterial, be adapted to remain at the furthest advanced position, subject to resetting, in any customary or well known manner.

Over the shaft 3 with its running index or hand is a cover 6, including a glass 7; and carried by such cover in a position to be associated with the running index or with its shaft, is an auxiliary index or hand 8. Advantageously this may be mounted for instance by a grooved collar 9 fast to or integral with the index hand 8; and cooperating in the groove a holding fork 11 is arranged such as to allow of movement as hereinafter more particularly set forth. The fork 11 is carried by an arm 12 which is secured at the end 13 to the cover in suitable manner, as by screw or rivet attachment to a metal plate 14 forming part of the cover assembly. Cooperating with the arm 12 is an optionally actuated means for raising or lowering the fork 11 and therewith the grooved collar 9 and the hand 8, whereby such hand may be seated down into engagement with the running hand 2 so as to be carried thereby or to be raised and held in suspended position free from such running hand. A leaf or guard 12' cooperates with the collar 9 and fork 11. Preferably, the arm 12 is of slightly resilient material tending normally to seat the collar 9 and the hand 8 in superposed position over the running hand 2. A lifting means, as a cam 15 on a stud 16 mounted through the cover, serves to raise the arm 12 and the collar 9 with its hand 8, when desired. A thumb lever 17 fastened to the outer end of the stud 16 provides for such actuation as desired.

Where preferred, a spring 18 may be arranged in connection with the stud 16 so as to insure of its being retained in either position to which the cam thereon may be swung.

In use, the shaft 3 being in motion proportional to the speed from the initial source will tend to move its connected indicating index 2 so as to show from moment to moment the running speed. The maximum hand 5 is also pushed along by the running hand 2 and is

retained at its furthest advanced position, until released, as by a pressure upon the release-button 19. The auxiliary hand 8 is normally set down into running position superposed on the hand 2 so as to move therewith. When it is desired to preserve an indication of the running speed at any given moment, the thumb lever 17 is thrown over, thus rocking the stud 16 and the cam 15, the latter then crowding the arm 12 so as to raise it and the fork 11 with the engaged collar 9 and auxiliary hand 8. The latter is thus separated from its drive and is retained in such position stationarily. When such stationary registration by the auxiliary index 8 is no longer desired, the thumb lever 17 is thrown back to reverse position, thus releasing the cam 15 from the arm 12 and the auxiliary hand 8 is then seated down on the running hand 2, to travel therewith in its varied movement. In order to insure uniformity of engagement with the hand 2, an interconnection with such hand or with the shaft 3 is provided, and preferably this may take the form of a pin 20 on the hand 8 engageable in a corresponding recess 21 on the running hand 2.

It will thus be seen that the device as a whole presents a running index showing the speed at all times and a maximum index, and further an optionally controllable index capable of preserving an indication of the running speed at any given moment. And the assembly moreover is of a compact character such as to simplify manufacture, as well as to insure accuracy and durability in usage.

Other modes of applying the principle of the invention may be employed, change being made as regards the details disclosed, provided the means stated in any of the following claims, or the equivalent of such, be employed.

I therefore particularly point out and distinctly claim as my invention:—

1. In a speed indicating device, the combination of a running speed index, and an optionally controllable means for retaining an indication of the running speed at any desired instant without stoppage of the running index and irrespective of whether the speed is decreasing or increasing.

2. In a speed indicating device, the combination of a running speed index, a maximum index, and an optionally controllable means for retaining an indication of the running speed at any desired instant without stoppage of the running index.

3. In a speed indicating device, the combination of a running speed index, and another index optionally controllable for retaining an indication of the running speed at any desired instant and irrespective of whether the speed is decreasing or increasing.

4. In a speed indicating device, the combination of a running speed index, a maximum index, and another index optionally controllable for retaining an indication of the running speed at any desired instant and irrespective of whether the speed is decreasing or increasing. 70

5. In a speed indicating device, the combination of a speed indicating shaft, a running index actuated thereby, and another index movable in relation and optionally retainable in a stationary position irrespective of whether the speed is decreasing or increasing. 75

6. In a speed indicating device, the combination of a speed indicating shaft, a running index actuated thereby, a maximum index, and another index movable in relation with the running index and optionally retainable in a stationary position. 80

7. In a speed indicating device, the combination of a speed indicating shaft, a running hand attached thereto, and another hand connectible to travel back and forth with said running hand and optionally disconnectible at any point. 85

8. In a speed indicating device, the combination of a speed indicating shaft, a running hand attached thereto, a maximum hand, and another hand connectible to travel back and forth with the running hand and optionally disconnectible at any point. 90

9. In a speed indicating device, the combination of a cover, a hand carried thereby adapted to be superposed on a running hand to travel back and forth therewith, and means for disengaging said hand from the running hand. 95

10. In a speed indicating device, the combination of a cover, a hand carried thereby adapted to be superposed on a running hand to travel back and forth therewith, and means mounted in the cover for lifting said hand from the running hand. 100

11. In a speed indicating device, the combination of a cover, a hand carried thereby adapted to be superposed on a running hand to travel back and forth therewith, and a manually controlled stud mounted through the side of the cover for lifting said hand from the running hand. 110

12. In a speed indicating device, the combination of a cover, a hand adapted to be superposed on a running hand, a grooved hub collar on said hand, a fork in the groove of said hub collar, an arm carrying said fork and mounted on the cover, and a cam for lifting said arm. 115

13. In a speed indicating device, the combination of a cover, a hand adapted to be superposed on a running hand, a grooved hub collar on said hand, a fork in the groove of said hub collar, a cam for lifting said arm, a stud carrying said cam and projecting 120

through the side of the cover, and a thumb lever on the projecting end of said stud.

14. In a speed indicating device, the combination of a cover, a hand adapted to be superposed on a running hand, a grooved hub collar on said hand, a fork in the groove of said hub collar, a resilient arm carrying said fork and mounted on the cover, a cam for lifting said arm, a stud carrying said cam and projecting out through the side of the cover, and a thumb lever on the projecting end of said stud.

Signed by me this 10th day of January, 1929.

15 EUGENE F. MARTINET.
